Primary Examiner — Catherine S Posthauer*Assistant Examiner* — Lynette Marie Sample(74) *Attorney, Agent, or Firm* — Daniel M. Cohn(57) **CLAIM**

The ornamental design for a lunch box as shown and described.

DESCRIPTION

FIG. 1 is a perspective view of a lunch box showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is a perspective view of the lunch box where the lunch box is in an open state.

The broken lines in the drawings depict portions of the lunch box that form no part of the claimed design.

1 Claim, 9 Drawing Sheets(56)
